UNITED STATES PATENT OFFICE

GEORGE H. BROWN, OF WILLOW GROVE, PENNSYLVANIA

HAT HOLDER

Application filed September 19, 1931. Serial No. 563,826.

The present invention relates to a hat holder particularly designed for use in vehicles such as automobiles and the like and the object of the invention resides in the provision of 5 a holder of this nature which is exceedingly simple in its construction, inexpensive to manufacture, thoroughly efficient and reliable in use and otherwise well adapted to the purpose for which it is designed.

With the above and other objects in view as will appear as the description proceeds, the invention resides in certain novel features of construction, and in the combination and arrangement of parts as will be hereinafter 15 more fully described and claimed.

In the drawings:

Figure 1 is a vertical section through a portion of an automobile body showing my improved hat holder in place.

Figure 2 is a sectional view taken substantially on the line 2—2 of Figure 1.

Figure 3 is a sectional view taken substantially on the line 3—3 of Figure 2, and

Figure 4 is a sectional view taken substantially on the line 4—4 of Figure 3.

Referring to the drawings in detail, it will be seen that the holder is of general U-shaped formation and includes a bight 5 curved longitudinally and at its ends merging into rearwardly and outwardly directed relatively short portions or extensions 6 which in turn merge into arcuate sides 7. Each of the sides 7 adjacent the open end of the frame is extended laterally outwardly and the laterally outwardly extended portion is provided with a return bend thus providing a bracket arm 10 opposite portions of which are offset adjacent the outer end of the arm and relatively twisted about one another as at 11 to provide at the outer end of the arm an eye to accommodate a fastening element 12 whereby the holder may be fastened to the top of an automobile body to extend substantially parallel 45 therewith as suggested in Figures 1 and 2 of the drawings.

The arms 10 in turn merge into arcuate arms 8 forming as it were continuations of sides 7, the arms 8 as shown being curved 50 reversely with respect to the sides 7 and serve

to contract or restrict the holder at the open end thereof.

The entire holder is made of resilient material and in actual practice, when the hat is placed within the holder to be supported 55 thereby as suggested in the drawings arms 8 are pressed outwardly away from one another permitting the hat to slide inwardly of the holder between the arms 8 so that the brim of the hat will rest on the sides 7 and the 60 arms 8 frictionally contact the crown of the hat to securely retain the same within the holder, said arms being provided on their outer free ends with knobs 9.

The manner of forming the bracket arms 65 10 permits of the arms 8 being sprung outwardly without danger of injury or distortion of the resilient holder.

It will be further noted, from a study of the drawings, that a hat holder is provided 70 whereby minimum contact of the holder with the crown of the hat is provided for, thus reducing to a minimum wear on the hat band as may be caused by a shifting of the hat relative to the holder, when for example the 75 holder is mounted in a vehicle; there being but three points of contact between the holder and the crown of the hat, these points of contact being where the arcuate bight 5 engages the hat, and where the arms or extensions 8 engage the hat, the major portion of the holder and especially the major portion of the arms 7 being retained in spaced relation with respect to the crown of the hat. Such will be readily apparent from a study 85 of Figure 3.

It is thought that the construction, operation, utility and advantages of the invention will now be quite apparent to those skilled in this art without a more detailed 90 description thereof.

It is apparent that changes in the details of construction may be resorted to without departing from the spirit or scope of the invention as hereinafter claimed or sacrificing 95 any of its advantages.

Having thus described my invention, what I claim as new is:

1. A hat holder comprising a single 100 length of wire bent to be generally elliptical

in shape, and having an open end and a closed end, the free ends of the wire adjacent the open end of the holder being reversely bent, loops opposite from each other adjacent the open end of the holder and twisted about 5 themselves to form supports for attachment to a wall, and the closed end of the holder having a relatively short arcuate bight inset therefrom.

2. A hat holder comprising a body formed from a single length of resilient material bent to be generally elliptical in shape and having an open end and a closed end, the sides of the holder at the open end of the body being reversely bent, and the closed 15 end of the holder having a relatively short arcuate bight inset therefrom, said body being also provided with attaching eyes extending in reverse direction from said sides of the holder.

20 In testimony whereof I affix my signature.
GEORGE H. BROWN.
